MEANS FOR SEALING PACKAGES

George B. Jinkerson, St. Louis, Mo.

Application November 14, 1938, Serial No. 240,330

5 Claims. (Cl. 229—47)

This invention relates generally to packages and more specifically to an improved means for sealing boxes or containers formed of corrugated board, fiber board and the like, the predominant object of the invention being to provide an improved means for sealing such packages which greatly simplifies the task of sealing the packages and which provides for sealing the packages in a more effective manner than was obtained when the methods heretofore followed were employed.

Prior to this invention packages of the type to which this invention relates were sealed in various ways, the most common methods being to seal the packages with gum tape, and by means of metallic fastening elements known as "stitches". Both of these methods are objectionable because of the time required to seal packages in accordance therewith, and also because they do not seal the packages securely and completely enough that they may not be opened by unauthorized persons in a manner to conceal the fact that the packages were tampered with.

The outstanding feature of the present invention is that packages sealed in accordance with the invention are so securely sealed that they are capable of withstanding extremely rough handling without having their seals broken, and also because of the particular manner of sealing the packages they may not be opened by an unauthorized person without the packages being so mutilated that the fact that they were opened would be readily apparent. Additionally the task of sealing packages in accordance with the present invention is so simple when compared with the sealing methods heretofore followed that much time and expense is saved to business organizations who pack, seal and ship out thousands of packages a day.

Briefly stated the invention disclosed herein comprises providing flaps or other portions of the packages, which are to be secured together to seal the packages, with metallic elements which are so located that cooperating metallic elements of related flaps are brought into contact with each other when the flaps or other portions of the packages are moved to their closed positions. These cooperating elements are then welded together with the aid of a suitable electrical or other welding apparatus to very securely and positively attach together the parts of the packages with which the metallic elements are associated. With the metallic elements welded together as described, and because said metallic

elements are very securely attached to the flaps or other sealed portions of the packages, the packages may be opened only by so completely mutilating the packages that the fact that they were opened would be very apparent.

Fig. 1 is a perspective of a box provided with the improved sealing means of the present invention.

Fig. 2 is a cross-section on a reduced scale taken through the box illustrated in Fig. 1.

Fig. 3 is an enlarged fragmentary section showing flaps of a box provided with the improved sealing means disclosed herein, the flaps being shown as they appear when being moved toward each other for the sealing operation.

Fig. 4 is a fragmentary section similar to Fig. 3, showing the flaps illustrated in Fig. 3 as they appear when the sealing operation is being performed.

Fig. 5 is a plan view of a fragment of a box flap having associated therewith one of the sealing members of the improved sealing means disclosed herein.

In the drawing, wherein is shown for the purpose of illustration, merely, one embodiment of the invention, A designates a box of the type to which the improved sealing means disclosed herein is applied. The improved sealing means disclosed herein may be applied to various types of boxes or packages which include overlapping flaps, but in order to show one type of box to which the improved sealing means is applicable the box A is illustrated in the drawing. This box includes side walls B, end walls C, end flaps D which extend inwardly from the opposed end walls at the tops and bottoms thereof, top flaps E and F which are hinged extensions of the side walls B and are movable to horizontal positions where the top flap E overlaps the top flap F to close the top of the box, and similar bottom flaps G and H, which are hinged extensions of the opposed side walls B and are movable to horizontal positions where the bottom flap H underlies the bottom flap G to close the bottom of the box. When the box A is closed at its top and bottom the end flaps D at the top of the box are disposed beneath the overlapped top flaps E and F, as shown in Figs. 1 and 2, and the end flaps D at the bottom of the box are disposed above the overlapped bottom flaps G and H as shown in Fig. 2.

Associated with the top flap E is a plurality of metallic plates 1, and associated with the top flap F is a like number of similar metallic plates 2, the plates 1 and 2 being so positioned with

respect to their associated flaps that said plates 1 will be located above and in contact with the plates 2 when the flaps E and F are moved to their horizontal positions where they close the 5 top of the box. Additionally the bottom flap H of the box is provided with a plurality of plates 3 and the bottom flap G is provided with a like number of similar plates 4. Here also when the bottom flaps G and H are moved to horizontal 10 positions to close the bottom of the box the plates 3 of the bottom flap H are disposed beneath and in contact with the plates 4 of the bottom flap G.

At the location of each of the plates 1, 2, 3, and 4, the associated flap is provided with a circular opening 5. Each of the plates is preferably, though not necessarily, circular in shape and each plate includes an outer marginal flange portion 6, which contacts with a face of the associated flap, and a circular, dished central portion 7 which is disposed in the circular opening 5 formed in the associated flap as shown in Figs. 3 and 4. The plates 1, 2, 3, and 4 are each secured to the associated flap by means of a plurality of rivets 8, each of these rivets being provided with a greatly enlarged head 8a which contacts with a face of the associated flap and a tubular shank portion 8b which extends through an aperture in the flap and through a hole in the flange portion 6 of the plate and is riveted over 25 in contact with the outer face of the flange portion 8 of the plate as indicated at 8c. Obviously the rivets 8 are provided with the greatly enlarged heads 8a so as to minimize the chance that the heads of the rivets might be pulled 30 through the material of the associated flaps to disengage the plates from the flaps.

By referring to Figs. 3 and 4 it will be noted that plates 1 and 2 of the flaps E and F are arranged in reversed relation with respect to 40 each other; that is to say, the plates 1 associated with the flap E are so disposed with respect to said flap that the marginal flanges of the plates contact with the top face of the flap and with the base walls 1' of the dished portions 7 of said plates approximately flush with the bottom face of the flap E, while the marginal flanges 45 of the plates 2 contact with the bottom face of the flap F and with the base walls 2' of the dished portions 7 of said plates 2 approximately flush 50 with the top face of the flap F. By so arranging the plates 1 and 2 of the flaps E and F, the base walls 1' and 2' of the cooperating plates are brought into close contact with each other when the flaps E and F are disposed in their horizontal 55 positions where they close the top of the box A. This is true also of the plates 3 and 4 associated with the bottom flaps G and H of the box, the cooperating plates of said plates 3 and 4 being arranged in reversed relation so that the 60 base walls of the dished portions of the cooperating plates will contact with each other when the flaps G and H are disposed in horizontal positions where they close the bottom of the box.

When the box A is to be sealed in accordance 65 with the present invention after the contents of the box have been packed therein, the end flaps D are first moved to their horizontal positions after which the side flap F is moved to a horizontal position above the end flaps D. The side 70 flap E is then moved downwardly to its horizontal position in which position the base walls 1' of the plates 1 of said flap E will contact with the base walls 2' of the plates 2 of the side flap F. It is to be noted that the base wall 1' of each 75 plate 1 of the side flap E is provided with an

aperture 9 formed therein and to make a seal between each pair of cooperating plates 1 and 2 the grounding element J of a suitable electrical welding apparatus (not shown) is introduced through the aperture 9 to contact with the associated plate 2. A suitable electrode K forming a part of the electrical welding apparatus is then touched to the plate 1, as indicated in Fig. 4, with the result that the cooperating plates 1 and 2 will be welded together. This sealing operation is repeated in connection with each pair of cooperating plates 1 and 2 to completely and securely seal the top of the box. The cooperating plates 3 and 4 of the bottom flaps of the box are welded together in like manner to seal the 15 bottom of the box, the base walls of the dished portions of the plates 3 associated with the flap H being provided with apertures through which the grounding element of the electrical welding apparatus is passed to contact with the base walls 20 of the plates 4 associated with the flap G and the electrode of the electrical welding apparatus being touched to the base walls of the plates 3 to make the welds.

From the foregoing it is plain that a box may 25 be very securely and completely sealed in an expeditious manner, the seals being of such nature that the box may not be opened by an unauthorized person without so mutilating the box as to make it obvious that the box has been 30 tampered with.

It is to be noted that end flaps D at the top and bottom of a box being sealed are interposed between the plates being welded and the contents of the box so that the contents of the box will 35 not be affected by the welding operation.

I claim:

1. In combination with a package having related portions adapted to be secured together to seal the package, metallic elements attached 40 to said related portions and adapted to be welded together to seal the package, one of said metallic elements being provided with means which aids in permitting electrodes of a welding apparatus to be brought in contact with both of said metallic elements.

2. In combination with a package having related portions adapted to be secured together to seal the package, metallic elements attached 50 to said related portions and adapted to be welded together to seal the package, one of said metallic elements having an opening formed therethrough through which an electrode of a welding apparatus may be passed to contact with the other of said metallic elements, said metallic elements including portions which are disposed in openings formed in said related portions of said package, and means for securing said metallic elements to said related portions of said package.

3. In combination with a package having related portions adapted to be secured together to seal the package, metallic elements attached 60 to said related portions and adapted to be welded together to seal the package, one of said metallic elements having an opening formed therethrough through which an electrode of a welding apparatus may be passed to contact with the other of said metallic elements, said metallic elements including central portions which are disposed in openings formed in said related portions 65 of said package and marginal flanges surrounding said central portions of said metallic elements, and means for securing said metallic elements to said related portions of said package.

4. In combination with a package having re- 70

- lated portions adapted to be secured together to seal the package, metallic elements attached to said related portions and adapted to be welded together to seal the package, said metallic elements including central portions which are disposed in openings formed in said related portions of said package and constitute the portions of the metallic elements which are welded together, and marginal flanges surrounding said central portions of said metallic elements, and fastening devices extended through apertures formed in said related portions of the package and in said marginal flanges of said metallic elements for securing said metallic elements to said related portions of said package, one of said metallic elements having an opening formed therethrough through which an electrode of a welding apparatus may be passed to contact with the other of said metallic elements.
- 5 10 15 20
5. In combination with a package having related portions adapted to be secured together to seal the package, metallic elements attached to said related portions and adapted to be welded together to seal the package, said metallic elements including central portions which are disposed in openings formed in said related portions of said package and constitute the portions of the metallic elements which are welded together, and marginal flanges surrounding said central portions of said metallic elements, and fastening devices extended through apertures formed in said related portions of the package and in said marginal flanges of said metallic elements for securing said metallic elements to said related portions of said package, said fastening elements being provided with greatly enlarged head portions adapted to prevent said fastening elements being pulled through the material of said related portions of the package, one of said metallic elements having an opening formed therethrough through which an electrode of a welding apparatus may be passed to contact with the other of said metallic elements.
